UNITED STATES PATENT OFFICE.

JASPER BAILEY THORN, OF GILLINGHAM, ENGLAND.

APPARATUS FOR CHECKING AND RECORDING RECEIPTS AND THE LIKE.

1,076,531.

Specification of Letters Patent.

Patented Oct. 21, 1913.

Application filed June 28, 1913. Serial No. 776,249.

To all whom it may concern:

Be it known that I, JASPER BAILEY THORN, a subject of the King of Great Britain and Ireland, and resident of Gillingham, county of Kent, England, have invented certain new and useful Improvements in Apparatus for Checking and Recording Receipts and the like, of which the following is a specification.

10 The present invention relates to that type of receipt checking and recording apparatus in which a receipt can be torn off from a strip of paper and given to the purchaser while at the same time a duplicate record is made on another strip within the apparatus and which can only be got at by certain accredited persons. In this connection it has been proposed to employ two strips of paper, one a receipt strip and 20 the other the record strip, and to automatically move such strips together in the required direction, the back of the receipt strip being coated or covered with a suitable transfer medium to enable a duplicate record to be made upon the record strip. Further, it is known that it has been proposed to employ a roll consisting of two paper strips and to feed such strips in the same direction on to a platform or table 30 located below an opening in the casing, the lower of the strips passing beneath a strip or sheet of carbon paper so that a duplicate of the receipt written on the upper strip is obtained; the strips are then moved 35 forward so as to carry the receipted portion of the upper strip out of the casing to be torn off and given to the purchaser while the duplicate or record is stored upon a roller located within the casing.

40 The present invention is described and shown in the accompanying drawings as applied to two strips of paper, the outer one of said papers being backed or coated with a transfer medium.

45 According to the present invention, the apparatus consists essentially of a cylindrical receptacle formed by two cases one of which is rotatable within the other in such manner that its rotation in one direction carries the receipt strip and record strip away from the writing position to

the tear-off position for the receipt strip and at the same time winding up the record strip, while the rotation of the case in the other direction brings a fresh portion of 55 the receipt strip and record strip opposite the writing position.

In the drawings: Figures 1 and 2 are diagrammatic sectional views, cover removed and casing in section, Fig. 1 being 60 the writing position and Fig. 2 the delivery position of the ticket for the purchaser. Fig. 3 is a side view of the inner case with paper in the writing position. Figs. 4 and 5 are exterior views seen from opposite 65 directions, showing the writing and delivery openings in the outer case.

Like letters of reference indicate corresponding parts.

Referring to Figs. 1 and 2, *a* is the outer 70 cylindrical case, box or frame having a side cover *C*, exposed through the broken away portions of said figures, and *b* is an inner cylindrical carrier rotatably mounted within said outer cylindrical case *a* also having 75 the side cover *a'*. On this carrier *b* are mounted upon the spindles *c* and *d* the reels *e* and *f*, said reel *e* being the supply reel for the double strip of paper *g* and reel *f* the storing reel for the record strip. The two 80 strips *g'*, *g*² of paper are led through an opening *h* in the side of the cylindrical carrier *b* and thence over a table portion *i* past the writing opening *j*—Figs. 1, 2 and 5—in case *a*. The strips then pass through 85 opening *k* in the side of the carrier *b* and the strip *g*² (the recording strip) led to the storing reel *f*. The other strip *g'* (the receiving strip) is passed through frictional rollers *m* and *n* which effect a grip 90 upon said strip *g'*, the two paper strips passing between the walls of the casings *a* and *b*, said casing *b* being as shown in Figs. 1 and 2 spaced from the cylindrical case *a* as at *b'* for that purpose. Roller *m* is geared 95 to roller *f* by gears *o*, *p*, *q*, *r*, *s*, gear *r* being loosely mounted on the spindle *t* carried by and fixed to the base of case *a* but capable of being connected to said spindle *t* by ratchet wheel *u* and pawl *v* carried by said 100 gear *r*, said wheel *u* being secured to said spindle. *w* is a gong rung on the comple-

tion of an operation by hammer x , its beveled projecting trigger tip y engaging stop z fixed on the outer case a , and b' , b' are studs carried by the cylindrical carrier b to engage with and pass through holes in the outer cover a' . The hammer x is pivotally mounted and is yieldingly held normally adjacent the gong by a spring x' interposed between said hammer and a fixed abutment x^2 . A purchase having been made, the assistant writes the amount on the strip g' showing at opening j and by reason of the table or platform i and the medium of the strip g' makes a duplicate impression on the strip g^2 . He then turns the cover a' which is loosely mounted on spindle t and case a and connected to the cylindrical carrier b in the direction of the arrow in Fig. 1, bringing case b into the position shown in Fig. 2, causing the reel f to be rotated by reason of gear r being locked to spindle t and thus draw in the recording strip g^2 and at the same time as this operation takes place roller m through gear o , p , q , will have been rotated, drawing forward the paper strip g' so that said strip will protrude through opening a^2 —Figs. 2 and 3—the strip being torn off against the edge a^3 of said opening a^2 . The movement of the carrier b in the direction of the arrow in Fig. 1 is limited by the stop z on the outer casing a striking against the ends b^2 and b^3 of the slot B in the said carrier b , as indicated by dotted lines in Figs. 1 and 2.

Having now described my invention, what I claim as new and desire to secure by Letters Patent of the United States is:—

1. A receipt check and recording apparatus including, in combination, a pair of relatively rotatable casing members nested one within the other, a supply reel carried by the inner one of said members and itself carrying a pair of paper strips, a storing reel adapted to wind thereon one of the strips, gearing operated by the relative rotation of said members and geared with the storing reel, and feeding means for the two strips also operated from the gearing by the relative rotation of said members.

2. A receipt check and recording apparatus including, in combination, a pair of relatively rotatable casing members nested one within the other, and one of said members having cut-off means, a supply reel carried by the inner one of said members and itself carrying a pair of paper strips, a storing reel adapted to wind thereon one of the strips, gearing operated by the relative rotation of said members and geared with the storing reel, and feeding means for the two strips also operated from the gearing by the relative rotation of said members, said members, the gearing, and the feeding means

being so arranged that the relative rotation 65 of said members in one direction carries the check receipt strip to a position for engagement with the said cut-off means and at the same time winds up the recording strip, while the relative rotation of said members 70 in the opposite direction brings fresh portions of both strips to writing position.

3. A receipt check and recording apparatus including in combination a pair of relatively rotatable casing members nested one 75 within the other, a center spindle fixed to the outer of said members, a supply reel carried by the other of said members and itself carrying record and receipt strips, a storing reel for the record strip having a 80 gear, friction rollers also carried by the member carrying the supply and record reels, a gear fast on the spindle, another gear loosely mounted on said spindle and being in mesh with the gear on the storing 85 reel, gearing connecting one of said friction rollers with the gear loosely mounted on the spindle, means for connecting the gear fast on the spindle with the one loosely mounted thereon, and stops to limit the travel of the 90 inner carrier.

4. A receipt check and recording apparatus comprising in combination, a cylindrical casing member provided with writing and delivery openings, a center spindle fixed to 95 said member, a cylindrical carrier rotatably mounted on the spindle and having a limited rotary movement in the said casing, a cover secured to the rotary carrier and cylindrical casing member, a supply reel mounted on 100 said carrier having receipt and record tapes wound thereon, means for unreeling the tapes and drawing the same over a portion of the side of the cylindrical carrier and before the writing opening in the casing 105 member, a reel for receiving the record tape, and gearing connecting the latter reel and the means for unreeling adapted to be operated upon the rotation of the cylindrical carrier toward the delivery opening.

5. A receipt check and recording apparatus comprising in combination an outer cylindrical casing member having writing and delivery openings, a spindle fixed in the center thereof, a cylindrical carrier having 115 its sides provided with slots rotatably mounted on the spindle, means for limiting the rotary movement of the carrier in the casing member, a supply reel rotatably mounted on said carrier having receipt and record tapes wound thereon, friction rollers journaled on the said carrier and adapted to draw the tapes through slots in the side thereof and over a portion of the same exposing the receipt tape through the writing opening in the casing member, a reel for receiving the record tape having a gear, gearing connecting the friction rollers with the

gear on said reel, a gear fast on the spindle, and means for connecting the latter gear with the aforesaid gearing upon moving the frame in one direction and thereby removing 5 the receipt portion of the strip from the writing opening to the delivery opening.

In testimony whereof I have affixed my signature in presence of two witnesses.

JASPER BAILEY THORN.
